UNITED STATES PATENT OFFICE.

LAWRENCE M. PERSONS, OF CHICAGO, ILLINOIS, ASSIGNOR TO COOK ELECTRIC COMPANY, OF CHICAGO, ILLINOIS, A CORPORATION OF ILLINOIS.

FUEL-FEED SYSTEM.

Application filed May 26, 1923. Serial No. 641,669.

My invention relates to fuel feed systems and more particularly to systems providing improved means for transferring liquid fuel from a relatively low to a relatively high 5 level, as may be used for example, for forcing fuel from the main fuel supply tank of a motor vehicle to the carburetor thereof.

One aim of this invention is to provide an improved fuel feed system of the character 10 indicated wherein the required amount of fuel is made available regardless of low speeds, high torque, or other unfavorable and varying running conditions of the vehicle.

15 Another object of this invention is to provide an improved fuel feed system for motor vehicles, which may be operated independently of mechanical connections to the vehicle engine.

20 Another object of my invention resides in the provision of an improved pumping mechanism for a system of the above indicated character, which mechanism is designed to prevent all possibility of leakage 25 of the fuel. To this end I have designed a suitable form of diaphragm pump, by the use of which the usual sliding pistons and packing rings are avoided. A further particular object of this invention is to adapt 30 the ordinary forms of inexpensive and efficient rotary motors to the operation of these diaphragm pumps.

A still further object of the invention is to provide a novel float operated switch for 35 controlling the operation of an electric motor driven fuel pump in the system comprising this invention, such switch being adapted to have its contacting parts immersed in the fuel at all times during their operation 40 in order to quench any arcing that may occur at the contacts. With this disposition of the contacting parts, the possibility of unintended ignition of the fuel is eliminated.

Another particular aim of my invention 45 is to provide an electric motor driven diaphragm fuel pump which will be simple to manufacture and install and which will possess great durability even when subjected to adverse operating conditions. Another 50 object of the particular structure here shown which embodies my invention is to provide a system, the parts of which may be easily and quickly disassembled for inspection, adjustment or repair.

To these and other ends the invention comprises certain novel features of construction and arrangement of parts, as will be herein-after more fully described and claimed, it being understood that various modifications may be made without departing from the 60 spirit of the invention and the intended scope of the appended claims.

In the present application I have shown one embodiment of my invention in which—

Figure 1 is a sectional elevation view 65 through an auxiliary tank and accompanying parts as embodied in the system;

Fig. 2 is a sectional view taken upon line 2—2 of Fig. 1;

Fig. 3 is a top plan view of the device 70 shown in Fig. 1;

Fig. 4 is a sectional view showing a modified type of device wherein an enclosed float operated switch within the auxiliary fuel tank is used; and,

Fig. 5 is a diagrammatic view of the electrical connections applicable to the device shown in Fig. 1.

In a general way the device shown in the drawings includes an auxiliary fuel tank 10 at the upper end of which, an electric motor operated diaphragm pump 11 is mounted. Fuel may be drawn to the pump 11 from the main fuel supply tank through an inlet check valve 12. Through an outlet check 85 valve 13 fuel may pass from the pump into the tank 10. An electric pump motor 14 may be mounted above the pump 11 on the tank 10. The fuel may pass through the outlet 15 at the bottom of the tank to 90 the carburetor of the motor vehicle engine.

As indicated in Fig. 5, the electrical circuit of the device may include a battery 16 in series with the motor 14 and with a float operated switch 17. The return side of the 95 circuit from the switch 17 to the battery 16 may be grounded, if desired. The switch 17 is so connected that when a float 18 is raised to its extreme upward position by floating upon the fuel when the tank 10 becomes 100 substantially filled with fuel, the circuit to the motor 14 will be opened.

The various parts of the system will now be described in further detail. The side walls of the tank 10 may comprise a cylinder 105 of sheet metal 19 provided with a rigid base 20, which is designed to permit drainage of the tank through a central plug opening 21.

The outlet 15 to the carbureter may also be formed in the base 20.

The pump 11, valves 12 and 13, and the electric motor 14 may be mounted as a unitary assembly upon a cover plate 22. The cylinder 23 of the pump 11 may be formed from sheet metal bent into a cup shape insertable into the upper end of the tank 10. The cylinder may be provided with an annular peripheral flange 24 resting upon a corresponding flange 25 formed at the upper edge of the tank 10.

A piston 26 of the pump 11 may preferably be of a flexible diaphragm type which 15 may embody a longitudinally flexible cylinder 27. The lower end of the cylinder 27 may be closed by a disc 28 soldered or otherwise sealed thereto while the upper end will be covered by the plate 22. An annular ring 29 may be sealed to the upper periphery of the cylinder 27 and will there rest upon the flange 24 of the cylinder 23 and beneath the periphery of the plate 22. As illustrated, suitable gaskets may be inserted between the plate 22, annular ring 29 and flange 24.

The valve 12 may comprise a body portion 30 formed with an inlet port as indicated at 31 and an outlet port at 32, both 30 of which communicate with a valve chamber 33 which may be covered by a screw cap 34. The valve member proper may comprise a flat disc 35 positioned over the inlet port 31 by pins 36 and 37, as shown in Fig. 3. As a result of its own weight, the valve member normally assumes its closed position, but may be easily raised by the inflowing liquid when the pump is actuated. As appears from Fig. 1, the valve member 40 35 is made easily accessible by merely removing the screw cap 34. Accordingly, if it is desired to inspect or replace this member, it will be unnecessary to disassemble any of the other parts of the device. The body 45 portion 30 may be soldered or otherwise fixed to the cover plate 22 which may be provided with an opening 37 registering with the outlet port 32 thus permitting the fuel to enter the cylinder 23 at a point to 50 one side of the piston 26.

The outlet valve 13 may be constructed in a manner very similar to the inlet valve 12 with the exception that its inlet and outlet ports will be reversed in position. An 55 inlet port 38 covered by a valve member 39 communicates with the space within the cylinder 23 and external to the piston 26. A valve chamber 40 is connected to the auxiliary tank through an outlet port 41 which 60 registers with suitable openings, as shown through the cover member 22 and the various peripheral flanges and gaskets above described.

The means for actuating the piston 26 65 will now be described. The small rotary

electric motor 14 may be mounted upon the upper side of the cover plate 22, as illustrated, and may be provided with a screw pinion 42, which engages a corresponding toothed wheel 43 fixed upon a crank shaft 70 44 which is journaled in bearings 45 and 46. The bearings 45 and 46 may be mounted upon the cover plate 22 in any suitable manner. The disc 28 at the inner end of the piston may be provided at its center with 75 a plug member 47, within which a connecting rod 48 may be rigidly fixed, the outer end of the connecting rod being pivoted to the crank 44. The plug member 47 may be sealed in the disc 28 by swaging or soldering at 49 and is preferably provided with a central chamber 50 for receiving a guide pin 51, which in turn is riveted to the cylinder head at 52. An annular flexible ring 53 as of rubber, may be fixed at the mouth 80 of the chamber 50 in a manner to embrace the pin 51 and thereby serve to yieldably guide the inner end of the piston in relation to the pin 51 and the cylinder walls. It will be noted that provision is thereby 85 made for a limited transverse movement of the piston as well as free longitudinal movement thereof.

The piston walls being longitudinally and transversely flexible, it is unnecessary to 90 provide a pivoted connection between the plug member 47 and the rod 48. Accordingly, with each turn of the crank 44, the piston will be longitudinally reciprocated and at the same time will be slightly transversely warped from side to side. Such transverse movement of the piston thus does 95 away with the necessity of an additional pivoted connection and accordingly renders the structure more durable and inexpensive 100 to manufacture and maintain.

The auxiliary tank 10 may be provided with a vent 53 in the form of a goose-neck tube, which permits the liquid level to become altered without varying the air pressure in the tank. The goose-neck form of tube serves to prevent the admission of dirt or foreign matter through the vent opening. 110

The float operated switch will now be described. A support bar 54 extending down 115 into the tank 10 may be fixed to the lower portion of the cylinder 23. A pair of lugs 55 and 56 may be formed at the lower end of the support bar 54 and serve to support a pair of cooperating yoke members 57 and 58, which are interconnected by a spiral tension spring 59. A pair of pins 60 and 61 serve to pivotally support the yoke members at their ends upon the lugs 55 and 56, respectively. A float 18 of any suitable design may be fixed to the yoke 57 by soldering to lugs 62, formed upon the yoke member. The yoke member 57 may be limited in its downward swinging movement by a stop pin 63 fixed in the lug 55 and in its upward 120 125 130

movement by a cushioning button 64 mounted upon the float 18 and contacting with the under side of the cylinder 23. The yoke member 58 may be limited in its upward swinging movement by a pin 65 fixed to the support bar 54 and in its downward swinging movement by an insulated contact member 66, which is also fixed in the support bar. A lead-wire 67 which may be insulated as by glass beads 68 may extend downwardly through the cover 22 and be connected to the contact 66. The spring 59 is so connected to the yokes 57 and 58 that it will tend to hold the yoke members inclined either in a downwardly biased position, or in an upwardly biased position, and while in the downward position the contact 66 will be grounded upon the yoke 58 thus completing a circuit through the motor 14. However, when the tank 10 becomes filled to a predetermined level, the float 18 will raise the yoke members into the upwardly biased position, thus abruptly breaking the circuit through the contact 66 and stopping the motor.

In the construction as above described, it will be noted that all of the working parts of the device, including the float operated switch, pump, motor and valves may be conveniently removed from the tank 10 in connection with the cover plate 22. Consequently, any adjustments and repairs that may be necessary may be very quickly accomplished. The cover plate 22 may be fastened upon the tank 10 in any suitable manner, as by screws at 69.

In the operation of the device, a switch 70 may be inserted in series with the circuit of the motor 14 and may be mechanically or otherwise associated with a switch 71 placed in the ignition circuit of the motor vehicle. Accordingly, when the ignition is thrown on preparatory to starting the vehicle, the fuel pumping motor will also be placed in the circuit and cause the piston 26 to be actuated. It will be evident that a fuel feed system may thus be provided by the above described structure, which will be in readiness for actuation at all times when the vehicle is to be operated. With each upward movement of the piston 26, a quantity of fuel will be drawn into the cylinder through the valve 12 and with each downward movement of the piston, the valve 12 will serve as a check valve and the fuel will be forced out into the tank 10 through the valve 13, which in turn will also act either as an air or liquid check level valve during the upward movement of the piston. After the ignition switch has been turned on, the motor 14 will continue to pump fuel into the tank 10 until the float 18 opens the circuit to the motor. A supply of fuel will thus be maintained in the tank 10 and a liquid head varying only within narrow limits will

be automatically maintained over the carbureter by the action of the float operated switch.

In the modification shown in Fig. 4, an enclosure 72 may be provided on the under side 70 of the cylinder 23 for housing a switch operated by a float 73. The float may be mounted upon a vertical guide rod 74, extending through a guide bracket 74 fixed to the base of the tank 10. A switch operating crank 76 extending to the outside of the enclosure 72 may be pivoted to a rod 77 fixed upon the float 73. Electrical connections may be made to the enclosed switch by means of a lead-wire 78. With this structure, the switch may be kept out of the fuel and at the same time be enclosed in order to prevent unintended ignition or explosion of the fuel. As in the previously described design, the switch and float are here removable with the cylinder 23 since the rod 74 may easily slide out of the guide bracket 73. It may be advantageous to use the enclosed switch modification under certain circumstances, as for example where a particular fuel is used which would interfere with proper electrical contacting at the switch if the contacts were immersed in such fuel.

Having thus described by invention, what I claim as new and desire to secure by Letters Patent in the United States, is:

1. A pump comprising a cylinder member having an open end and an extensible and contractible pumping element nested therein adjacent to said open end, the peripheral wall edges of said pumping element being sealed to the edges of said cylinder member at said open end to form a closed pumping chamber having the usual inlet and outlet, a tank enclosing said pumping element and said cylinder and receiving the fluid pumped by said pumping element, a cover for said tank, a motor for driving said pumping element, and a driving connection extending through said cover and connecting said motor to said pumping element.

2. A pumping unit comprising the combination with a tank for receiving the fluid pumped, of a pumping element and a cylinder arranged in nested relation at and within one end of the tank, a motor mounted on said tank at said end, and a driving connection extending from said motor into said tank for driving said pumping element.

3. A pumping unit comprising the combination with a tank having an open end and adapted to receive the fluid pumped, a pumping element, a cylinder enclosing said pumping element, said pumping element and said cylinder being nested in said tank within said open end, a cover for said tank, a motor for driving said pumping element on said cover, and a driving connection extending through said cover and into said

tank to connect said motor with said pumping element.

4. In a fluid supply system, a tank, a removable cover thereon, a pumping device of the diaphragm type for supplying fluid to said tank mounted upon said cover within said tank, a rotary motor mounted upon said cover externally of said tank and operatively connected to said device, and a float operated switch for controlling said apparatus within said tank.

5. In a fluid supply system, a tank, a removable cover thereon, electrically operated pumping apparatus mounted upon said cover for supplying fluid to said tank, and a float operated switch for controlling said apparatus mounted within the tank upon said apparatus.

6. In a fluid supply system, a tank, a removable cover thereon, electrically operated pumping apparatus mounted upon said cover for supplying fluid to said tank, and a float operated switch mounted upon said cover within the tank, said switch serving to open the circuit of said electrical pumping apparatus when the fluid reaches a predetermined level, and said switch being submerged when the fluid rises to said predetermined level.

30 7. A pumping unit comprising a pumping element, a cylinder member enclosing said pumping element, a tank in which said cylinder member and pumping element are nested at one end for receiving the fluid pumped by said pumping element, a motor for driving said pumping element, a plate to which said tank, said cylinder member and said pumping element are attached, said plate serving as a mounting for said motor, and a driving connection extending through said plate to connect said motor to said pumping element.

8. In a fluid supply system, a tank having an open end formed with a flange, a pump cylinder member insertable in said open end, said cylinder member also having an open end formed with a flange for surmounting said first named flange, and a longitudinally flexible piston member insertable in said open ended cylinder member and adapted to deliver the fluid pumped into said tank, said piston member being provided with a flanged outer edge for surmounting said cylinder flange.

55 9. In a fluid supply system, a tank having an open end formed with a flange, a pump cylinder member insertable in said open end, said cylinder member also having an open end formed with a flange for surmounting said first named flange, a longitudinally flexible piston member insertable in said open ended cylinder member, said piston member being provided with a flanged outer edge for surmounting said cylinder flange, a cover for said tank surmounting said piston member,

and valves mounted upon said cover for the admission of fluid into said cylinder member and escape of fluid from said cylinder member into said tank.

10. In a fluid supply system, a tank, an electrically operated pumping device for supplying combustible fluid to said tank, and a float operated submerged switch within said tank for controlling the operation of said pumping device. 75

11. In a fluid supply system, a tank, an electrically operated pumping device for supplying fluid to said tank, and a float operated submerged snap switch within said tank for controlling the operation of said pumping device, said switch being removable from the tank as a unitary assembly. 80

12. A fuel feed pump comprising a tank for receiving the fuel pumped and an outlet associated therewith, a cylinder at one end of said tank, said cylinder having a flange thereon for closing said end of the tank, a cover for closing said cylinder, a flexible walled piston in said cylinder, said piston being secured in position between said cylinder and said cover to form a closed pumping chamber having the usual inlet and outlet, actuating means carried upon said cover for operating said piston, and a mechanical connection extending through said cover for operably connecting said actuating means and said piston. 85 90

13. A fuel feed pump comprising a tank for receiving the fuel pumped and an outlet associated therewith, a pump cylinder nested within the upper end of said tank, said cylinder having an open upper end, a flexible walled piston operating solely within said cylinder and closing said open end of said cylinder to form a closed pumping chamber having the usual inlet and outlet, a cover for said piston, power driven means supported by said cover, and an operable connection passing through an opening in said cover and connecting said piston to said power driven means. 100 110

14. A fuel feed pump comprising a tank and an outlet associated therewith, a pump cylinder nested within the upper end of said tank, said cylinder having an open upper end, a flexible walled piston operating solely within said cylinder and closing said open end of said cylinder to form a closed pumping chamber, a cover for said piston, power driven means supported by said cover, an operable connection passing through an opening in said cover and connecting said piston to said power driven means, and valve units also supported by said cover so as to be accessible without removing said cover or any of the associated parts, said units having passages therein to provide communication between said chamber and said tank and also between a source of fuel supply and said chamber. 115 125 130

15. A fuel feed pump comprising a tank for feeding fuel by gravity from an outlet associated therewith, a pump cylinder supported at the upper end of said tank for feeding fuel thereinto from a suction chamber formed within said cylinder and having the usual inlet and outlet, a flexible walled piston extending into and operable within said cylinder, said piston having its periphery so connected substantially at one end of said cylinder as to produce a suction in said chamber when said piston is flexed, electrically operated actuating means for said piston, means for supporting said actuating means, said supporting means being arranged to enclose said cylinder and said piston within said tank preferably at one end thereof, and a mechanical connection extending from said actuating means into said piston and connecting therewith to operate said piston. 15
